APPARATUS FOR FORMING CONCRETE
SLABS

Roy A. Badt, Beverly Hills, Calif.

Application January 10, 1947, Serial No. 721,209

7 Claims. (Cl. 25—131.5)

1

The present invention relates to concrete constructions in general and particularly to concrete slab constructions. More specifically the invention comprises and relates to the construction of concrete slabs by the use of removable metal forms in conjunction with open-web beams.

In the construction of concrete floors the floor proper is commonly supported by girders which may be of either structural steel or reinforced concrete. The girders are usually connected by a multiplicity of beams, also either steel or concrete, and these together with the overlying concrete slab form an integral floor which, of course, may also be a roof.

Heretofore in the forming of the concrete slab it has been common practice to employ steel forms or molds which extend between the beams and which may be variously shaped, as for example inverted channels. These steel forms after being positioned are usually supported by underpinning or the like and are adapted to support the concrete slab which is then poured thereon to encase the beams and the girders, or at least the upper parts thereof, to produce an integral floor or roof construction.

The concrete slab-supporting forms as used and as supported according to current practice are usually cumbersome to position and difficult to remove. Additionally, the resulting construction involves the inherent disadvantage that if a ceiling is to be positioned therebelow, it must be spaced an appreciable distance below the beams in order to provide the necessary space for the usual electrical conduits and other installations. This is usually accomplished by hanging long galvanized wires from the concrete slab to the lower ends of which metal channels are attached to support the ceiling construction which may be plastered.

According to the present invention a concrete floor or roof slab is constructed by the use of removable metal forms secured between open web I-beams in a manner permitting of ready removal. The I-beams are braced to prevent side buckling or lateral deflection by suitable bridging beams removably secured in place and cooperating with the open web permanent I-beams to support the forms during the pouring of the concrete. These bridging beams may be left in place permanently if desired. According to the present invention it is unnecessary to space the ceiling below its overlying supporting structure to provide for the electrical conduits and other installations for they may extend through the open web of the I-beams. Each of the forms

2

used in the molding of the concrete is removable for reuse and with a minimum of effort. The resulting concrete construction conforms to accepted practice.

6 It is, accordingly, an object of the present invention to provide an improved construction or organization for use in the making of concrete floor or roof slabs.

It is another object of the invention to provide a new and improved cooperative organization including removable forms for the making of concrete floor or roof slabs supported by open web beams.

A still further object of the invention is to provide an improved organization of parts including forms and supporting beams for the construction of reinforced concrete slabs.

These and other more specific objects will appear upon reading the following specification and claims and upon considering in connection therewith the attached drawings to which they relate.

Referring now to the drawings in which preferred embodiments of the present invention are disclosed:

25 Figure 1 is a view in perspective of an illustrative section of the construction comprising the present invention prior to the positioning of the reinforcing steel mesh and the pouring of the concrete slab;

30 Figure 2 is a partial view of the construction of Figure 1 after the concrete slab has been poured;

Figure 3 is a vertical section upon the line 3—3 of Figure 2 and shows the mounting of the bridging members in the open web of the I-beam and the support of the reinforcing mesh by the chair nails driven through the forms into the wooden stringers;

35 Figure 4 is a vertical section upon the line 4—4 of Figure 3 and illustrates the method of supporting the removable form from the I-beam by means of flange clips and also the seating for the bridging members;

Figure 5 is a section upon the line 5—5 of Figure 3 and illustrates the retention of the forms upon opposite sides of the I-beam by means of a web clip;

Figure 6 is a view in perspective of a flange clip; Figure 7 is a view in perspective of a web clip; Figure 8 is a view in perspective of a chair nail;

50 Figure 9 is a perspective view of a section of a construction comprising a second preferred embodiment of the invention making use of a different arrangement of parts and omitting the reinforcing mesh in the concrete slab; and

55 Figure 10 is a perspective showing of the re-

taining means for the bridging beam as embodied in the second embodiment of the invention.

Reference is now made to Figures 1 to 8 of the drawings in particular, in which the first preferred embodiment of the invention is illustrated. The reference character 11 indicate an I-beam generally comprising upper and lower flanges 12 connected by a web 13 formed along its length with spaced openings 14. The presence of these apertures in the web causes the I-beam to be known as an open web I-beam and it represents a well known and accepted structural form characterized by its relatively great strength as related to its weight. In the drawings, only partial lengths of the I-beams 11 are shown but it is to be understood that they extend between girders arranged at right angles thereto and to which they are suitably secured at their ends. The construction comprising the present invention may be continuous along the length of the beams so that the disclosure of a portion of the length thereof is illustrative of the entire construction.

While the I-beams 11 are fixedly secured at their ends to the unshown supporting girders and are steel members of great strength and rigidity, yet it is desirable that they be braced and reinforced at intervals at least until the concrete slab which they are to support is sufficiently hardened. To accomplish this reinforcing function, bridging members 16 are provided having a length slightly greater than the spacing of the webs 13 of the I-beams and carrying seat angles 17 at their ends. Angles 17 are preferably welded in place and each includes a base 18 slotted at its opposite sides at 19 in a manner which enables it to straddle the web 13 of beam 11 at the inclined sides of an opening 14 therein. Slots 19 are spaced by the distance which should properly separate the webs of the I-beams 11 and with bridging members extending between the beams, preferably between alternate openings 14 therein, the I-beam is held rigidly against deflection.

The preferred form of retaining means for the bridging beam is as described but it is to be understood that other forms than the slotted seat angle 17 may be used, as for example the form illustrated in Figure 10. In the type illustrated in Figure 10 a rigid angle member 21 is welded to the bridging beam 16 and is formed with a base 22 extended perpendicularly therefrom. Spaced bolts 23 extend through the base 22 and adjacent their headed ends carry enlarged washers 24. The bases 22 of the angle members are spaced by a distance representing the proper spacing of the outside faces of the web 13 of beams 11 and are adapted to pass through the openings 14 and then, upon lateral movement of the carrying I-beam 16, to overlap the face of the web adjacent to the opening. The bolts 23 are so positioned that the washers 24, upon the bolts being tightened, clamp the web 13 between themselves and the base 22.

The concrete slab to be supported by the beams 11, whether it be a floor or a roof, should preferably be so formed as to enclose and encase the beam's upper flange 12 in each instance. The thickness of the slab is variable depending upon many factors and will or will not include reinforcing means depending upon the strength characteristics desired. To support the concrete after it has been poured and before it has set, removable forms are provided according to the present invention which extend between adjacent I-beams 11. These forms are indicated in the drawings by the reference character 25 and each is seen to

comprise a relatively large flat top surface 27 connected at one side by an inclined beveled corner 29 to a perpendicularly extending relatively narrow side wall 28. The side 28 is adapted to abut and rest flat against the I-beam web 13 and to be supported in that position with the flat surface 27 of the form at a level slightly below the upper flange 12 of the beam by means of flange clips 31. These are shown in place performing their function in Figure 4 and alone and in perspective in Figure 6. Clip 31 will hereinafter be described in greater detail but at this point it is only stated that it extends through a slot 32 in the adjacent flat surface 27 of the form 25 and underlies that surface in supporting relationship.

Each form 25 extends slightly more than half-way from its supporting I-beam 11 toward the apposing I-beam 11 and is lapped by a duplicate and cooperating form 26 identically supported by the apposing beam. This relationship is clearly illustrated in Figures 1 and 2 in which are also shown the stringers 34 positioned as to support the forms at these lapped portions. Stringers 34 are preferably of wood, extend parallel to the I-beams 11, and are themselves supported by the bridging beams 16. Suitable shim blocks 36, which may also be of wood, are positioned below the bridging beams 16 in order to support the forms 36 at the desired level and also to provide means upon the displacement of which the stringers may readily be loosened after the concrete has set. The forms and the stringers are additionally retained in their desired relative positions by means of chair nails 37 shown performing their intended function in Figure 2 and illustrated in perspective in Figure 8. Each nail is seen to comprise a straight central portion connected to sharpened ends extending perpendicularly thereto by oppositely facing angle sections which serve to position the sharpened ends equidistant upon opposite sides of the central portion. With the sharpened ends of the nails extending downwardly through slots 38 formed in the surfaces 27 of the forms 26, the central portion of each nail extends angularly. This angular relationship of the nail bodies is used advantageously in the manner illustrated in Figure 2 to support a steel support bar 39 which in turn centrally supports the reinforcing steel mesh 41 which also rests upon the upper I-beam flanges 12 and more specifically upon the flange clips 31 which extend thereacross.

The overlapping forms 26 are secured to their supporting I-beams 11 so that the edges or end walls 28 thereof make close contact with the beam web 13 by web clips 43 illustrated in detail in Figure 7 and in their functionally operative positions in Figure 5. The flange clips 31 and the web clips 43 will hereinafter be described in detail but at this point attention is directed only to the fact that each web clip is adapted to extend through slots 44 in the end wall 28 upon opposite sides of the web 13. Vertically spaced pairs of slots 44 being spaced along the end walls 28 in a manner such that at least one pair is positioned adjacent each web opening 14. The web clip in place functions to draw the forms 26 against the opposite sides of the web and with several clips positioned along the length of each form, it is held securely in place.

With the various parts arranged as described, the construction is now ready for the pouring of the concrete slab which is laid to the desired depth as illustrated in the drawings. In this connection it is to be understood, of course, that

the exact dimensions and proportions are not of the essence of the invention for they are variable within the limits permitted by good design. After the pouring of the concrete into a slab, indicated in the drawings by the reference character 46, the entire construction is given the necessary time period for hardening into a self-supporting and unitary mass. Before discussing the removal of the forms, attention will be given to the flange and web clips which have previously been referred to generally.

The flange clip 31, shown in detail in Figure 6, comprises a strap-like element of metal shaped to provide a flat top wall portion 47 of a length sufficient to overlie the I-beam flange 12. One end 48 is turned downwardly and inwardly to extend under the flange 12 in locking relationship. The opposite end, 49, extends at right angles to the top wall 47 and a triangular flap or tongue 51 is carried thereby, extending at right angles. Flap 51 may be stamped from the end 49 and its presence leaves a lower flap 52 which, at the time the flange clip is positioned upon the I-beam, lies in the plane of the end wall 49. The latter is so dimensioned as to extend snugly into and through a slot 32 formed in the top wall 27 of form 26, as illustrated clearly in Figure 1. When so positioned, the flap or tongue 51 overlies the top surface of the form and the tongue 52 is positioned therebelow. Tongue 52 when so positioned is bent at right angles to itself into the position illustrated in dotted lines in Figure 6 at which time it locks the form against downward displacement. Preferably the distance separating the two tongues is substantially the width of the form top wall 27. As is clearly illustrated in Figure 1, the flange clips 31 are arranged along the I-beams with the tongue-carrying sides 49 extended upon both sides thereof so as to support the forms 26 upon both sides.

Referring now particularly to the web clips 43, they are seen to comprise a strap-like member of a width approximately that of the flange clip 31 and have a flat top surface 56 and a right angle end 57 integral therewith. A geometrical figure is stamped from the top wall 56, as indicated at 58, to leave a tongue member 59 the inner extremity of which is spaced from the inner surface of end 57 by a distance equal to the distance which should separate the spaced faces of form end walls 28 upon opposite sides of an I-beam 11. The clips 43 are adapted to extend through the spaced slots 44 arranged along the form end walls 28 in the manner illustrated in Figure 5. When so positioned, the end 57 lies adjacent one form end wall 28, the top wall 56 extends through apposed slots 44 and also through the opening 14 of the web 13 positioned therebetween. The tongue 59 is bent at right angles to itself from the full line position shown in Figure 7 to the dotted line position in which it will also extend at right angles to the slot 44 and so function to hold the end walls 28 against the web 13 and also lock the clip against displacement. This relationship is clearly illustrated in Figure 5.

After the entire unit has set for the necessary time period for the concrete to harden as to be self-supporting, the forms and the supporting structure can be removed. The first step in this operation comprises the removal of the shims 36 which may be driven from below the stringers by a hammer or other driving tool. With the shims displaced the bridging beams 16 can then be removed if desired. With the form of angle

seat illustrated in Figures 1 and 2, this displacement requires only the forcing of the seat upwardly sufficiently to displace the web from the angle seats or slots 19 whereupon the attached bridging member 16 can be removed. The operation is repeated for each bridging beam. If the bridging seat elements illustrated in Figure 10 are employed, the worker need only loosen the bolts 23 to permit of removal. In either event the removal operation is a fairly obvious one.

After the removal of the various bridging beams, the stringers 34 can be displaced. They are held only by the downwardly extending pointed ends of the chair nails 37 and can be pried free with a minimum of effort. Thereafter it is necessary only to break off, as by hammer blows, the tongues 52 and 59 of the flange clip 31 and the web clip 43, respectively, and the forms 26 are free for downward displacement aside, possibly, from a slight adherence to the concrete. The presence of the form slots 38, through which the chair nails 37 extend, permits of lateral displacement of the forms from the beams should displacing movement in that direction be desired. Their removal completes the dismemberment of the removable structural elements. Of course, if desired, all of the aforescribed parts can be left in place but for purposes of economy their reuse will usually be contemplated.

The removal of the various forms and their supporting means leaves a unitary construction in which the concrete slab 46 is supported by the spaced beams 11 and, of course, at the ends of the beams by the girders which are unshown but which are of the usual type. As previously suggested, if a ceiling is to be placed below the slab it may be connected directly to the lower flanges 12 of the I-beam and without spacing for conduits and other installations can be run transversely through the beams and specifically through the openings 14 formed in the webs 13 thereof.

Referring now specifically to the second preferred embodiment of the invention illustrated in Figure 9, a modified construction is shown employing certain of the basic concepts of the first described embodiment. The spaced I-beams are again indicated generally by the reference character 11 and include upper and lower flanges 12 spaced by a web 13 formed with longitudinally spaced openings 14. The bridging beams 16 of the first embodiment are again employed but are retained this time by the seating means disclosed in Figure 10. The stringers 34 are again carried by the bridging beams 16 though resting directly upon shims 36. In the present form two or more stringers are preferably positioned between each of the I-beams 11.

The removable metallic forms of the present invention are quite different from forms 26 of the first embodiment and are indicated generally by the reference character 66. Each form is shaped as an inverted channel member and includes a top surface 67 connected to perpendicular end walls 68 by a bevelled corner 69. Each end wall is formed at its lower extremity with an inturned slotted supporting foot or flange 71 along the length of which are arranged slots 72. In the first embodiment the form 26, it will be remembered, was formed with an end wall 28 upon only one end but in the present embodiment each side of the form 66 includes an end wall 68 and the forms are so arranged that the end walls 68 extend between the adjacent I-beams 11 rather

than lying adjacent to one of them. This arrangement brings the transversely extending end wall 68 of the form into alignment with the end walls of an adjacent form 66 in the manner clearly illustrated in Figure 9, the flanges 71 resting upon the stringers 34. The forms are again lapped and to make this possible one end is made slightly larger than the other to permit of telescoping, or, the natural resilience of the form may be relied upon to enable it to be spread sufficiently that its cooperating counterpart may be slid therein.

Transversely extending slots 73 are formed at the ends of each form top wall 67 and through these slots extend the flange clips 31, previously described, which perform the identical function ascribed to them in the first embodiment. In this form of the invention reliance is placed solely upon these clips and upon the stringers 34 for the proper positioning of the forms.

In this the second embodiment of the invention the concrete reinforcing means comprising the mesh 41 of the first embodiment is omitted and the slab, here indicated at 74, again rests directly upon the supporting forms and encases the top flange 12 of the I-beams.

The method of removal of the supporting form structure in this embodiment is similar to that of the first embodiment with necessary variations to accommodate the differences in construction. The shims 36 are again first removed, whereupon the bridging member 16 and the stringers 34 can be displaced. Thereupon, and after the removal of the supporting tongues 52 of the flanges 31, or at least their deformation back into a plane permitting their passage through the slots 73, the forms 66 can be displaced.

While the particular construction herein shown and described in detail is fully capable of attaining the objects and providing the advantages herein before stated, it is to be understood that it is merely illustrative of the presently preferred embodiments of the invention and that no limitations are intended to the details of construction or design herein shown other than as defined in the appended claims.

I claim:

1. Apparatus for forming a concrete slab upon a supporting open web I-beam comprising a removable form extended from said I-beam, a flange clip overhanging said beam and supporting said form therefrom, and a web clip extended through the open web of said beam and connecting said form thereto.

2. Apparatus for forming a concrete slab upon a supporting open web beam having an upper flange comprising a removable form including a top surface and an end wall, a flange clip overlying said flange of said beam and connected to the top surface of said form to support same, and a web clip extended through the open web of said beam and connected to said end wall to secure same to said web.

3. Apparatus for forming a concrete slab upon a supporting open web beam having an upper flange comprising a removable form including a top surface and an end wall, said top surface and said end wall being formed with openings, a flange clip overlying the flange of said beam and extended through an opening in said top surface

to support said form, and a web clip extended through the open web of said beam and through an opening in said end wall to secure said wall to said web.

4. Apparatus for forming a concrete slab upon a supporting open web beam having an upper flange comprising removable forms upon opposite sides of said beam each including a top surface and an end wall, flange clips overlying said flange of said beam and connected to the top surfaces of said form, and a web clip extended through a web opening of said beam and connecting the end walls of said forms upon the opposite side thereof.

5. Apparatus for forming a concrete slab upon a supporting open web beam having an upper flange comprising removable forms upon opposite sides of said beam each including a top surface formed with spaced slots and an end wall formed with spaced slots, flange clips overlying said flange and extended through the slots in said top surfaces to support said forms, and web clips extended through the slots in said end walls and therebetween through an opening in the beam web to secure said end walls to said web.

6. Apparatus for forming a concrete slab upon a supporting open web beam having an upper flange comprising a removable form including a top surface and an end wall, a flange clip overlying said flange of said beam and connected to the top surface of said form to support same, a web clip extended through the open web of said beam and connected to said end wall to secure same to said web, and means to support said form at a point spaced from said beam including a bridging beam secured to said open web and extended rigidly below said form.

7. Apparatus for forming a concrete slab upon a supporting open web beam having an upper flange comprising a removable form including a top surface and an end wall, a flange clip overlying said flange of said beam and connected to the top surface of said form to support same, a web clip extended through the open web of said beam and connected to said end wall to secure same to said web, means to support said form at a point spaced from said beam including a bridging beam secured to said open web and extended rigidly below said form, and a stringer extended parallel to said beam and spacing said form from said bridging beam.
